UNITED STATES PATENT OFFICE.

CLAUDE C. WESTERMAN, OF BREMEN, OHIO.

TUB.

Application filed September 19, 1927. Serial No. 220,499.

This invention relates to tubs of that type generally known as "slack tubs" used for chilling metals during the tempering process.

It is an object of the present invention to provide a device of this character designed primarily for use in tempering the sharpened cutting edges of steel bits, means being employed whereby bits can be properly supported in the tub during the tempering operation, the position of the edge of the bit being such that steady flow of cool water can be directed against said edge.

A further object is to provide a tub of this character which can be quickly drained to prevent freezing of water therein when the tub is not in use.

A further object is to provide a tub having the interior parts removable so that the tub can be cleaned readily and the parts re-placed by the ordinary mechanic.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

In the accompanying drawings, the preferred form of the invention has been shown.

In said drawings,

Figure 1 is a top plan view of the tub. Figure 2 is a central vertical longitudinal section therethrough, the water pipe being shown partly in elevation.

Figure 3 is a section on line 3-3, Figure 2.

Referring to the figures by characters of reference 1 designates a heavy sheet metal trough having a rounded bottom, the upper edges of this trough being turned outwardly and downwardly to provide reinforcing and protecting flanges 2. The ends of this trough are welded or otherwise connected to heads 3 likewise formed of heavy sheet metal having outturned base flanges 4 for engaging a supporting surface. One of these heads has a drain opening 5 near the top thereof and both of the heads are provided, on their inner faces, with supporting brackets 6 held to the heads by welding or in any other suitable manner, each bracket being formed with spaced recesses 7. Both brackets are designed to engage and support the ends of supporting rods 8 which bear firmly against

the heads and can be formed of heavy pipe. At intermediate points the rods 8 bear upon and are braced by a plate 9 in the form of a web which is welded or otherwise attached to the bottom portion of the trough and has a space 10 extending into the bottom edge thereof so that this web can thus bridge the water supply pipe 11 extending longitudinally within the trough. This pipe 11 is mounted in one end only of the tub and is provided, along its uppermost portion, with a longitudinal series of apertures 12 through which jets of water can flow into the tub. A single outlet opening 13 can be provided in the bottom of the pipe 11 near one end, this opening being used for draining purposes.

It is to be understood that the pipe 11 is to be connected by a pipe to a source of water supply and water flowing into the pipe 11 will escape through the openings 12 and fill the trough up to the level of the overflow aperture 5.

The tub herein described is designed primarily for use in tempering the cutting edges of bits used in drilling wells. After a bit has been sharpened and heated it is lowered into the tub so as to rest on the rods 8. The heads of the bit will be presented toward the pipe 11 and will be quickly chilled by the jets of fresh water flowing into the tub from the openings 12.

As shown particularly in Figure 1 the pipe 11 can be readily disconnected from the tub inasmuch as this pipe is supported in one of the end plates or heads 3 and held thereto by nuts 14 arranged to grip said head or plate. Thus the pipe can be withdrawn from the tub and the rods 8, when not in use, can be driven upwardly out of position in the tub, thereby exposing the interior of the tub so that it can be cleaned readily.

In cold weather, while the tub is not in use, the water can be drained therefrom by providing a three-way valve 15 at the outer end of the pipe 11. By turning this valve in one direction it can open into a vent 16 so that the contents of the tub and of the pipe 11 can thus drain through the vent.

What is claimed is:

1. A tub of the class described including a trough, end plates or heads connected thereto, a water supply pipe extending longitudinally within the bottom portion of the tub and having apertures for directing jets of water upwardly into the tub, sup-

porting rods extending longitudinally within the tub above the supply pipe.

2. A tub of the class described including a trough, end plates or heads connected thereto, a water supply pipe extending longitudinally within the bottom portion of the tub and having apertures for directing jets of water upwardly into the tub, supporting rods extending longitudinally within the 10 tub above the supply pipe, and means carried by the bottom portion of the trough for supporting said rods at intermediate points.

3. A tub of the class described including a trough, end plates or heads connected 15 thereto, a water supply pipe extending longitudinally within the bottom portion of the tub and having apertures for directing jets of water upwardly into the tub, supporting rods extending longitudinally within the 20 tub above the supply pipe, and means carried by the bottom portion of the trough for supporting said rods at intermediate points,

said rods being detachably mounted on the supporting means and the heads of the tub.

4. A tub of the class described including a trough, heads connected to the ends thereof and constituting supports, one of said heads having an overflow opening, a water supply pipe detachably connected to one of the heads and extending longitudinally within 25 the tub, said pipe having outlet openings in the upper portion thereof for directing jets of water upwardly within the tub, there being a drain opening in the bottom of the pipe, brackets integral with the inner faces 30 of the heads, a supporting member carried by the bottom of the tub and bridging the pipe, and spaced supporting rods mounted on said member and upon the brackets, said rods being removable.

In testimony that I claim the foregoing as my own, I have hereto affixed my signature.

CLAUDE C. WESTERMAN.
